UNITED STATES PATENT OFFICE.

THOMAS H. NOXON, OF INGERSOLL, ONTARIO, CANADA.

SEEDING-MACHINE.

SPECIFICATION forming part of Letters Patent No. 434,292, dated August 12, 1890.

Application filed December 5, 1889. Serial No. 332,617. (No model.)

To all whom it may concern:

Be it known that I, THOMAS HENRY NOXON, manufacturer of agricultural implements, of the town of Ingersoll, in the county of Oxford, 5 in the Province of Ontario, Canada, have invented a certain new and useful Improvement in Seeding-Machines, of which the following is a specification.

The object of the invention is, first, to construct that portion of the frame from which the drag-bars are suspended in a simple, cheap, and light manner; secondly, to provide easy means for adjusting the drag-bars to bring them closer to each other or farther 15 apart, in order to enable the drill-rows to be made any desired distance apart, and, thirdly, to provide simple means for adjusting the teeth or hoes on their drag-bars to any desired angle to regulate the depth at which 20 they will enter the soil; and it consists, essentially, first, of a drag-bar shaft connected at each end to the axle-bracket by two bars—one extending horizontally to the base of the axle-bracket and the other diagonally to an 25 arm extending from the said bracket—the said shaft being journaled in a bracket fixed to the bottom of the tongue; secondly, of drag-bar clips fitted onto a drag-bar shaft having a longitudinal groove formed in it to receive 30 a rib formed on the journal surface of each clip, in order that the said clips may be independently adjusted longitudinally upon the said shaft and at the same time be held from revolving on it, and, thirdly, in the peculiar 35 formation of the drag-bar head and projections extending from the drill-hoe or cultivator-tooth by which the angle of the said drill-hoe or tooth may be readily adjusted without removing a bolt.

40 Figure 1 is a perspective view of that portion of the frame to which the drag-bars are connected. Fig. 2 is a detail of one of the drag-bar clips. Fig. 3 is a perspective view of the drag-bar head and top of the drill-hoe or cultivator-tooth. Fig. 4 is a sectional elevation 45 of the same parts. Fig. 5 is a detail of the mechanism for locking the drill-hoe or cultivator-tooth in position. Fig. 6 is a detail of lifting-chain connection.

A is the drag-bar shaft supported at each 50 end by two bars B and C, the bar B extending horizontally to the bottom of the axle-bracket D, while the bar C extends diagonally to an arm E, projecting from and formed upon the axle-bracket D, thus constituting a 55 strongly-braced support for each end of the drag-bar shaft A. A bracket R, fixed to the bottom of the tongue S, forms a bearing for the center of the shaft A, and midway between this counter-bracket and the ends of 60 the shaft A, I preferably provide stiffening-bars T.

With the view of enabling an easy longitudinal adjustment of the drag-bars F, I make a longitudinal groove a in the drag-bar shaft 65 A, and on the journal surface of each drag-bar clip G, I form a rib b to fit into the groove a. When the nuts H, which hold the cap of the clip in position, are tightened, the said clip G is held rigidly to the drag-bar shaft A, 70 and by loosening the said nuts the said drag-bar clips may be independently adjusted longitudinally upon the drag-bar shaft A, and held in any desired position by simply retightening the said nuts. Of course the same effect 75 will be produced by making a rib on the drag-bar shaft or making the drag-bar angular in cross-section, in order to prevent the clip from revolving on the drag-bar shaft, while permitting it to be adjusted longitudinally. By thus 80 making the drag-bar clips adjustable upon the drag-bar shaft the drag-bars may be moved closer to each other or farther apart, in order that the farmer may readily adjust the drill-hoes or teeth of his machine to make the drill-rows any desired distance apart. The hand-lever I is suitably supported on a bracket 85 fixed to the tongue of the machine, and is connected by the rod J to the crank K, which is fixed to the drag-bar shaft A. It follows, 90 therefore, that the movement of the hand-lever I will cause the drag-bar shaft A to revolve, and as the drag-bars are alternately connected to their respective clips on opposite sides of the drag-bar shaft A the rolling 95 of the said drag-bar shaft will cause the desired zigzagging of the teeth or hoes. As the shaft A cannot be raised or lowered for the

purpose of altering the angle of the teeth or hoes, it is necessary that the teeth or hoes should be connected to their respective drag-bars in such a manner that their angle may be readily altered. This I accomplish in a simple manner and without the necessity of removing a single bolt. On reference to Sheet 2 of the drawings the details of construction of this portion of my invention will be found 10 fully illustrated.

L is the drag-bar head pivoted on the end of the drag-bar and held in position by the spring-dog M. A notched projection N extends from the top of the head L, and from 15 the base of this projection the face of the head is shaped, as indicated, to receive the faces of the projections O P, formed on the head of the drill-hoe or cultivator-tooth. The projection O is shaped, as indicated, to fit 20 into any of the notches d, formed on the projection N, while the projection P is merely the base of the T-bolt Q, which is designed to fit into an elongated slot U, formed in the drag-bar head, as indicated. In order to insert 25 this T-bolt Q in the said slot, it is necessary to turn the tooth or hoe in a horizontal position, and when it resumes its normal position the T-head of the said bolt Q extends across the slot and holds the projection P 30 against the head L. When the T-bolt Q is inserted in the slot U and the tooth or hoe swings around to resume its normal position, the spring-bolt V is held clear of the slot U by the hand, so as to permit the T-bolt Q to be at or near the bottom of the slot U, in order 35 that the projection O may clear the lip d', formed on one side of the notched projection N. When the tooth or hoe is adjusted to the desired angle, it is raised up, so as to force 40 the projection O into the desired notch in the projection N, which will hold it in the said position. When thus raised up, the spring-bolt V springs out under the T-head of the bolt Q, thus locking the said bolt and 45 preventing the projection O from falling out of its notch. From this description it will be seen that it is merely necessary to push the spring-bolt V clear of the T-head of the bolt Q, when the projection O may be dropped 50 clear of the notched projection N and moved so as to come opposite to the particular notch which will hold it in the desired new position.

With the view of providing simple means for the purpose of detachably connecting the 55 lifting-chains to their respective drag-bars, I form upon the drag-bar head L an arm W, which extends back onto one side of the drill-hoe or tooth-head. On the side of the arm W next to the face of the tooth or hoe I form 60 a fork X, into which one of the links of the chain Y is inserted. In order to retain the chain in this fork, I form a flange Z on the face of the hoe or tooth head, which projects over the forked end of the arm W when the 65 tooth or hoe is fixed to the drag-bar head L.

With the view of permitting the easy rocking of the head of the tooth or hoe while being adjusted to the different angles, I convex the face of the projection N, or that portion of the drag-bar head L against which the 70 said projection fits, or I may convex both the said surfaces.

With the view of preventing the lateral movement of the projection O in the slot, I can either provide the lip d, already described, 75 on one side of the notched projection N, or I might place them on both sides, or instead of the lip being formed on the notched projection N a lip could be formed on one or both sides of the projection O.

I have spoken of the bolt Q as being T-headed. It will of course be understood that an L-headed bolt would answer quite as well. In fact, a bolt with a head of any form which will prevent it passing a slot made to receive 85 its shank would answer. If I used a round-headed bolt, I would of course have to make a round hole near the bottom of the slot U. All the other parts would work exactly the same, except that it would not be necessary 90 to turn the hoe or tooth in a horizontal position in order to form the connection between it and the drag-bar head.

What I claim as my invention is—

1. In a seeding-machine, the combination 95 of the tilting drag-bar shaft, the drag-bars connected thereto, the drag-bar heads connected to said bars and having the notched projection, the slotted extension, the arm, the fastening device, the cultivator or drill tooth-head having a projection for engaging the notched projection of the drag-bar head, a pin or stud for engaging the slotted extension and retained in place by the fastening devices of the drag-bar head, and an opening 100 or openings to receive the ends of the said arm of the drag-bar head.

2. The drag-bar head L, having a notched projection N extending from it, in combination with the upwardly-extending projection 110 O, formed upon the head of the cultivator tooth or hoe, and with the headed bolt Q, extending from the face of the projection P and fitting into the elongated slot U, and a spring-bolt V, designed to support the hoe or 115 tooth, substantially as and for the purpose specified.

3. The arm W, extending from the drag-bar head L, and having a fork X formed on it to receive the chain Y, in combination with 120 the flange Z, extending from the side of the head of the cultivator tooth or hoe, substantially as and for the purpose specified.

4. In a seeding-machine, the combination 125 of the drag-bars F, the drag-bar head L, connected thereto and having the arm W, and the cultivator-head adapted to be connected to or engaged by said arm.

5. In a seeding-machine, the combination 130 of the tilting drag-bar shaft, the drag-bar

clips laterally adjustable on said shaft, the drag-bars connected at one end to said clips, the drag-bar heads connected to the other end of the drag-bars, said drag-bar heads having a notched projection and a slot, the cultivator-head having a projection engaging the said notched projection, a bolt entering the slot of the drag-bar heads, and an arm on the

drag-bar heads engaging the cultivator-heads, substantially as described.

Toronto, October 16, 1889.

THOMAS H. NOXON.

In presence of—

CHARLES C. BALDWIN,
F. R. CAMERON.
